REFRIGERATION SYSTEM

Filed Sept. 23, 1929

UNITED STATES PATENT OFFICE

1,943,608

REFRIGERATION SYSTEM

Paul G. Hollinger, Chicago, Ill.

Application September 23, 1929
Serial No. 394,705

9 Claims. (Cl. 62—115)

My invention relates to improvements in refrigeration systems, and it consists in the combinations, constructions, and arrangements herein described and claimed.

5 An object of my invention is to provide a refrigeration system of the multiple type in which novel means is employed whereby the usual float valve constructions associated with the cooling units may be entirely dispensed with.

10 A further object is to provide a refrigeration system of a type employing a minimum amount of pipe in that a single pipe is connected with each cooling unit in lieu of the usual two pipe construction.

15 A further object is to provide a refrigeration system of the multiple type in which a minimum number of valves is employed and in which the valves are so arranged that the latter are easily reached and grouped in such a manner that a 20 relatively simple construction is employed.

A further object is to provide a refrigeration system of the multiple type in which means is provided whereby an effective operation is attained regardless of the height of the building 25 in which the system is installed.

A further object is to provide a refrigeration system of the multiple type in which all of the operating valves are grouped and associated with the condensing apparatus whereby the necessity for providing valves in the living quarters is entirely eliminated.

Other objects and advantages will appear in the following specification, and the novel features of the invention will be particularly pointed out in the appended claims.

My invention is illustrated in the accompanying drawing, forming part of the application, in which

40 Figure 1 is a diagrammatic view of the refrigeration system embodying my invention,

Figure 2 is an enlarged detail view of a portion of my device,

Figure 3 is a sectional detail view of one of the valves employed, and

45 Figure 4 is a diagrammatic view of the cams embodied in my invention.

In carrying out my invention, I make use of a compressor 1 which may be driven by a motor 2 through the medium of a belt 3. The compressor is operatively connected with a condenser 4 by means of a pipe 5. The condenser is associated with a receiver 6. The latter is connected with the pipe 5 by means of a pipe 7. A pipe 8 leads from the receiver 6 to a valve 9. The condenser may also be placed in com-

munication with the valve 9 by means of a pipe 10. The pipe 8 is extended as at 11 and is operatively connected with a valve 12.

A short pipe 13 is associated with the valve 12 and is connected with a section of a pipe 14 which is provided with a valve 15. One end of the pipe 14 is associated with an elbow 16 which supports one end of a pipe 17. The latter is connected with a pipe 18 through the medium of an elbow 19. One end of the pipe 18 is provided with a flexible tube 20 which is connected with a pipe portion 21 operatively connected with a receiver 22. The receiver is provided with a loop 23 for receiving one end of a lever 24 which is fulcrumed as at 25 upon a bracket 26 which may be mounted upon the wall of a building or any other suitable supporting structure. The lever is provided with a weight 27 which may be moved upon the lever for changing the distance of the weight from the fulcrum. 75

The pipe 21 is connected with the receiver near the top of the latter. The receiver is also provided with a pipe 28 which is located near the bottom of the receiver. The pipe 28 is provided with a flexible connection 29 which is 80 associated with a valve 30. The valve 30 is associated with a pipe 31. The latter is connected with a valve 32. The pipe 14 is extended as at 33 and is in communication with the valve 32 by means of a pipe 34. The pipe 33 is provided 85 with a by-pass construction 35. The pipe 33 is connected with a pipe 36 which also communicates with the pipe 31 as indicated by the pipe 37. The pipe 36 leads to a pressure control 38. A pipe 39 leads from the pressure control to a 90 pipe 40 which is connected with the compressor 1 and the condenser 4 as well as the receiver 6.

In Figure 3 I have shown a sectional detail view of the construction of the valves 9, 12, 15, 30, and 32. Since all of the valves are identical 95 in construction, the description of these valves will be confined to a single construction. The valve 9 shown in Figure 3 comprises a hollow body portion 41 having openings 42 and 43 therein for receiving the pipe 10 and the pipe 44 which is 100 connected with the pipes 8 and 11 shown in Figure 1. The body portion is provided with a valve seat 45 which is arranged to close the passageway between the pipes 10 and 44. The body portion is provided with an opening 46 105 through which a valve stem 47 associated with a valve 48 projects. The outer end of the valve stem is provided with a suitable washer 49 against which one end of a coil spring 50 bears. The other end of the spring rests upon the end of the 110

body portion. The spring 50 normally tends to hold the valve 48 firmly in its seat 45. The coil spring 50 and that portion of the stem 47 which projects to the exterior of the body portion 5 are enclosed within a flexible cap 51.

In Figure 1 I have shown the valve 9 as being provided with a rocker arm 52 which is pivotally supported at 53. One end of the rocker arm is provided with a roller 54 which is disposed in engagement with the surface of a drum 55. The valves 12, 15, 32, and 30 are provided with similar rocker arms 56, 57, 58, and 59, respectively. All of the rocker arms are identical in construction and operation. The drum 55 is provided with a plurality of raised portions or cam portions 60, 61, 62, 63, and 64. In Figure 3 I have shown the rocker arm 52 as being provided with a threaded opening 65 for receiving a pressure member 66. The latter is provided with a lock nut 67 for rigidly fixing the pressure member with respect to the rocker arm. Each rocker arm is provided with an identical pressure member. Preferably, the inlet opening in the valve body 41 and the outlet opening are so arranged that the pressure will always tend to hold the valve firmly in its closed position. One end of the body portion is closed by means of a plug 68. The latter may be soldered for providing a sealed closure. The body portion is provided with a flange 69 whereby the valve may be rigidly secured upon any suitable supporting structure as indicated at 70 by means of suitable bolts 71.

Referring now to Figure 2, it will be noted that the drum 55 is mounted for rotation upon suitable bearings 72. The latter may be mounted upon the supporting structure 70 which may be of any suitable panel like construction. The support 70 may also be a part of the floor in the building where the installation is made if it is desired to mount the equipment in a horizontal plane rather than in a vertical arrangement as disclosed in the drawing. The drum is provided with a shaft 73 which carries a worm gear 74. The latter is disposed in mesh with a worm 75 which is associated with a motor 76. The gear ratio is such that a relatively low speed of the drum 55 is attained.

In Figure 1 I have shown a pipe 77 as leading from the compressor 1 to the pipe 33. The compressor motor 2 is provided with a conductor 78 which leads to the source of current. A second conductor 79 leads from the motor to the pressure control 38. A conductor 80 leads from the pressure control to the source of current associated with the conductor 78. Thus it will be seen that the circuit through the motor may be opened and closed by reason of the pressure control 38 as will be more fully explained later.

In Figure 1 I have shown a conductor 81 leading from the conductor 80 to the motor 76. A conductor 82 leads from the motor 76 to a conductor 83. The conductor 83 is positioned for permitting electrical connection with a conductor 84 connected with a conductor 85 which leads to the conductor 78. One end of each of the conductors 83 and 84 is disposed in operative relation with respect to the weight 27, whereby the movement of the weight in one direction will tend to establish electrical connection between the two conductors and movement of the weight in the opposite direction will open the circuit at this point. The opposite ends of the conductors are positioned in operative relation with respect to the drum 55. These ends tend to move into

electrical contact at all times. When, however, the drum 55 is in the position shown in Figure 1, the conductors are moved apart by reason of a lug 86 which is carried by the drum. A slight rotation of the drum will move the lug out of engagement with the conductor 83, whereby the latter will move into electrical connection with the conductor 84.

The pipe 31 is extended as at 87 and 88, whereby branch pipes 89 and 90 may be operatively connected with the portion 88. The lines 89 and 90 pass to the various floors in a building and provide means whereby cooling units 91 associated with refrigerators 92 may be operatively connected with the refrigeration system. Service valves 93 to 99, inclusive, may be provided.

In Figure 1 I have shown the pressure control 38, the motor 2, the compressor 1, and the condenser as being mounted upon a supporting base 100.

From the foregoing description of the various parts of the device, the operation thereof may be readily understood. One side of the valve 30 is operatively connected with the bottom of the receiver 22. The other side of the valve is operatively connected with the cooling units by means of the pipe 31 of the portions 87 and 88 and the branches 89 and 90. The valve 30 permits the passage of liquid refrigerant from the receiver 22 to the cooling units. It will be noted in Figure 105 4, which is a diagrammatic plan view of the cam arrangement upon the drum 55, that the valves 9, 12, 15, 32, and 30 are opened and closed at different times and that the operation of these valves is entirely determined by reason of the cams. The 110 valve 32 prevents liquid refrigerant from passing to the lower part of the compressor 1 during the charging period of the system. The by-pass 35 permits a limited amount of liquid refrigerant to pass to the compressor even though the valve 32 115 is closed.

The valves 12 and 15 may be placed in communication with the receiver 22 through the pipe 17. In other words, these valves communicate with the upper part of the receiver. The valves 12 120 and 15, together with the valve 9, control the pressure within the receiver 22. The opposite side of the valve 15 is connected with the low side of the compressor. The valve 12 holds the liquid refrigerant in the receiver 6 during the 125 period of reduced pressure within the receiver 22. The valve 9 controls the operation of the condenser 4, the pressure on the high side of the compressor, the receiver 6, and also the receiver 22. This may be termed the charging period. During the time that the valve 9 is closed, the condenser will tend to fill with liquid refrigerant. At this time the compressed vapor is not condensed by the condenser but passes directly to the receiver 6.

For the purpose of describing the operation of the system, let it be assumed that the valve 30 is closed. At this time the valve 32 will be opened, the valve 15 closed, the valve 12 opened, together with the valve 9. The refrigerant vapor is drawn from the top of the cooling units through their respective pipe connections, through the pipe 31, the valve 32, and into the compressor. The vapor at this time of course is compressed and passed to the condenser 4 where the vapor 145 is converted to liquid. Liquid from the condenser passes through the valves 9 and 12, the pipe portions 17, 18, 20, and 21, and into the receiver 22. The liquid passed to the receiver is held therein by reason of the fact that the valve 30 is closed. 150

The receiver 22 will be gradually filled with the liquid refrigerant. When a predetermined amount of liquid refrigerant has been passed into the receiver 22, the receiver will tend to move downwardly against the influence of the weight 27. Such movement of the receiver will cause an elevation of the weight, at which time the conductor 83 is moved into electrical connection with the conductor 84 for closing the circuit through the motor 76.

Operation of the motor will cause a rotation of the drum 55 through the medium of the gears 74 and 75. Almost simultaneously with the closing of the circuit through the conductors 83 and 84, the lug 86 will be moved out of engagement with the conductor 83, whereby the opposite ends of the conductors are also placed in electrical connection. At this time the contacts are arranged in parallel. The electrical connection caused by the moving away of the lug 86 permits a complete rotation of the drum 55. When the drum has completed its rotation, the lug 86 is moved into engagement with one of the conductors for breaking the circuit. As soon as any of the liquid refrigerant is removed from the receiver 22, the latter of course will decrease in weight, whereby the weight 27 will tend to move the receiver back to its original position whereby the circuit influenced by the weight 27 will be opened.

The drum 55 rotates slowly. During the rotation, the valve 9 will be closed, whereby higher pressure is built upon the receiver 6. This pressure is conveyed through the pipe 8, the valve 12 which is still open, through the pipe 17, back to the receiver 22. This pressure is applied to the liquid in the receiver 22 for a short time. As the drum continues to move, the valve 32 closes and the valve 30 opens immediately. This permits the liquid refrigerant to flow into the pipe 31 and to the various cooling units in the system. When the valve 32 has been closed, a certain amount of liquid refrigerant passes the by-pass 35 and enters the compressor, thereby maintaining normal pressures. As the drum continues to rotate, the valve 12 closes, thereby cutting off the pressure upon the refrigerant liquid in the receiver 22. The valve 9 then opens for permitting the normal operation of the condenser 4 but the condensed liquid refrigerant is held in the receiver 6 by reason of the valve 12. The valve 15 now opens, and, since the valve is provided with a throttle action, the pressure within the receiver 22 will be removed gradually. Any liquid refrigerant in the cooling units above the inlet openings therein and in the pipe lines leading to the cooling units returns to the receiver 22 through the valve 30. The valves are now again in the positions defined above in connection with the description of the operation of the system. When the drum 55 has completed its rotation, the lug 86 moves the conductor 83 out of electrical engagement with its companion conductor for breaking the circuit through the motor 76. The pressure control 38 is arranged to break the circuit through the motor 2 when the pressure reaches a predetermined low point. When, however, the pressure increases, the pressure control 38 will function to close the circuit through the motor 2 for operating the compressor.

It will thus be seen that I have provided a system in which each cooling unit is provided with a single opening for admitting the refrigerant fluid to the cooling units and also for conveying the refrigerant vapor from the cooling units

to the compressing means. By reason of this construction I have entirely dispensed with the usual float valves, whereby a relatively simple construction is required. A relatively small number of valves is necessary, and it will be noted that the number of valves does not increase, regardless of the number of cooling units associated together in a single system.

The condenser 4 may be any one of the various standard types now employed in refrigeration systems. Some of the condensers are air cooled, while others are cooled by liquid, usually water. In case it may be desired to use a liquid cooling medium in connection with my system, the pipe 44 is preferably disconnected from communication with the pipe 8, at which time the pipe 44 may be connected with a liquid supply, whereby the liquid may be circulated through the pipe 10 and through the cooling coils in the condenser. The water of course passes from the coils associated with the condenser through any suitable means. Under these conditions, the valve 9 will function as a controlling means for the circulation of the cooling medium. When using the pipe line 10 in connection with the liquid cooling medium, the upper end of the pipe 7 is connected with the bottom of the condenser 4 rather than with the pressure pipe 40, as shown in Figure 1.

It will be understood of course that the cams 105 to 64, inclusive, may be changed in length for adjusting the operation of the cam drum to suit various conditions. In other words, some of the cams may be lengthened and under certain conditions shortened. While I have mentioned the 110 elimination of float valves, it will be understood of course that the usual expansion valves are also eliminated by reason of my structure.

In Figure 4 I have indicated the contact positions of the rollers associated with the rocker 115 arms during the cooling period, at which time the circuit through the motor 76 is opened as shown in Figure 1. The direction of rotation of the drum is indicated by the arrow in Figure 2.

I claim:

1. In a refrigeration system, a movable, liquid-refrigerant receiver, a cooling unit, valve-controlled connections between the receiver and said cooling unit, and power means influenced by the movement of said receiver when the latter 125 has been provided with a definite amount of refrigerant liquid for causing a movement of the latter within the system.

2. In a refrigeration system employing a compressor and a condenser, a movable, liquid-refrigerant receiver, cooling units, valve-controlled means for placing said receiver in communication with said compressor and said condenser, and power means influenced by the movement of said receiver for causing a movement of the 135 liquid refrigerant within the system.

3. In a refrigeration system employing a compressor and a condenser, a movable, liquid-refrigerant receiver, cooling units, valve-controlled means for placing said receiver in communication with said compressor and said condenser, power means influenced by the movement of said receiver for causing a movement of the liquid refrigerant within the system, and pressure-controlled means for starting and stopping the compressor when the pressure within the system has reached a predetermined low point or a predetermined high point.

4. In a refrigeration system, a movable, liquid-refrigerant receiver, cooling units, valve-con-

- 5 trolled connections between the receiver and
said cooling units, electrically controlled means
influenced by the movement of said receiver when
the latter has been provided with a predeter-
5 mined amount of refrigerant liquid for causing
a movement of the liquid refrigerant within the
system, and pressure-controlled power means
for condensing refrigerant vapor within the sys-
tem and forcing the liquid to the refrigerant re-
10 ceiver.

15 5. In a refrigeration system employing a compressor and a condenser, a movable, liquid-re-
frigerant receiver, cooling units, valve-controlled
connections between the receiver and said cool-
15 ing units, each of said cooling units being pro-
vided with a single connection with said valve-
controlled connections, and power means in-
fluenced by the movement of said movable, li-
quid-refrigerant receiver when a predetermined
20 amount of refrigerant liquid has been conveyed
thereto for causing a movement of the refrigerant
liquid within the system.

25 6. A refrigerating apparatus comprising a liquid-refrigerant container, a cooling unit, a single pipe line for providing communication be-
tween the container and the cooling unit, a valve connected with the pipe line for cutting off com-
munication between the container and the cool-
30 ing unit, means for withdrawing gaseous refrigerant through the single pipe line from the cool-
ing unit, liquefying said refrigerant and forcing the liquid-refrigerant into the container, and
means for opening the valve when the liquid-
35 refrigerant in the container exceeds a predeter-
mined amount whereby the liquid-refrigerant
may be forced through the single pipe line and
into said cooling unit.

40 7. In a refrigerating apparatus, the combina-
tion of a liquid-refrigerant container, a cooling
unit, pipe means for providing communication
between the container and the cooling unit, a valve connected with the pipe means for cutting
45 off communication between the container and
the cooling unit, means for withdrawing gaseous
refrigerant from the cooling unit, liquefying said
refrigerant and forcing the liquid-refrigerant
50 into the container, means for opening the valve
when the liquid-refrigerant in the container ex-
ceeds a predetermined amount whereby the
liquid-refrigerant may be forced into said cool-
ing unit, and means for releasing the pressure
on the liquid-refrigerant in the container sub-
sequent to the filling of the cooling unit with
the liquid-refrigerant whereby the surplus liquid-
refrigerant may return to the container.

55 8. In a refrigerating apparatus, the combina-
tion of a liquid-refrigerant container, a cooling
unit, a compressor and a condenser, pipe means
in communication with the container, the cool-
ing unit, the compressor and the condenser, a
60 plurality of valves connected with the pipe
means, and valve actuating means, certain of said
valves being operable by the valve actuating
means whereby the compressor and condenser
respectively may withdraw and condense gaseous
65 refrigerant from the cooling unit, the condenser
forcing the condensed refrigerant into the con-
tainer, certain of said valves being operable by
the valve actuating means when the liquid-
refrigerant in the container exceeds a predeter-
70 mined amount, whereby the liquid-refrigerant
may be forced from the container into the cool-
ing unit, and certain of the valves being operable
by the valve actuating means subsequently to the
filling of the cooling unit with the liquid-refrig-
75 erant, whereby the surplus liquid-refrigerant
may return to the container.

80 9. In a refrigerating apparatus, the combina-
tion of a liquid-refrigerant container, a cooling
unit, a compressor and a condenser, pipe means
in communication with the container, the cool-
ing unit, the compressor and the condenser, a
85 plurality of valves connected with the pipe means,
and valve actuating means, certain of said valves
being operable by the valve actuating means
whereby the compressor and condenser respec-
tively may withdraw and condense gaseous re-
90 frigerant from the cooling unit, the condenser
forcing the condensed refrigerant into the con-
tainer, certain of said valves being operable by
the valve actuating means when the liquid-
refrigerant in the container exceeds a predeter-
95 mined amount, whereby the liquid-refrigerant
may be forced from the container into the cool-
ing unit, and certain of the valves being operable
by the valve actuating means subsequently to the
filling of the cooling unit with the liquid-refrig-
100 erant, whereby the surplus liquid-refrigerant
may return to the container.

105 9. In a refrigerating apparatus, the combina-
tion of a liquid-refrigerant container, a cooling
unit, a compressor and a condenser, pipe means
in communication with the container, the cool-
ing unit, the compressor and the condenser, a
110 plurality of valves connected with the pipe means,
and valve actuating means, certain of said valves
being operable by the valve actuating means
whereby the compressor and condenser respec-
tively may withdraw and condense gaseous re-
115 frigerant from the cooling unit, the condenser
forcing the condensed refrigerant into the con-
tainer, certain of said valves being operable by
the valve actuating means when the liquid-
refrigerant in the container exceeds a predeter-
120 mined amount, whereby the liquid-refrigerant
may be forced from the container into the cool-
ing unit, and certain of the valves being operable
by the valve actuating means subsequently to the
filling of the cooling unit with the liquid-refrig-
125 erant, whereby the surplus liquid-refrigerant
may return to the container, said valve actuating means
comprising a rotatable cam means operatively
connected with the valves and a power means for
rotating said cam means.
